(57) **CLAIM**

The ornamental design for a housing for a lighting system, as shown and described.

DESCRIPTION

FIG. 1 is a top, front, left-side perspective view of a housing for a lighting system according to our new design;

FIG. 2 is a top, rear, right-side perspective view thereof;

FIG. 3 is a bottom, front, right-side perspective view thereof;

FIG. 4 is a front elevation view thereof;

FIG. 5 is a rear elevation view thereof;

FIG. 6 is a left-side elevation view thereof;

FIG. 7 is a right-side elevation view thereof;

FIG. 8 is a top plan view thereof;

FIG. 9 is a bottom plan view thereof; and,

FIG. 10 is a top perspective view thereof, shown in an environment of use.

The dash-dash broken lines in the drawings are for the purpose of illustrating environmental subject matter and portions of the housing for a lighting system that form no part of the claimed design.
